UNITED STATES PATENT OFFICE.

HEINRICH KOPPERS, OF ESSEN-ON-THE-RUHR, GERMANY, ASSIGNEE TO K. KOPPERS COMPANY, OF CHICAGO, ILLINOIS, A CORPORATION.

OVEN FOR GENERATING GAS AND PRODUCING COKE.

1,134,683.

Specification of Letters Patent.

Patented Apr. 6, 1915.

Original application filed July 28, 1913, Serial No. 781,463. Divided and this application filed October 21, 1914. Serial No. 887,875.

To all whom it may concern:

Be it known that I, HEINRICH KOPPERS, a subject of the King of Prussia, and residing at Essen-on-the-Ruhr, Germany, have invented a new and Improved Oven for Generating Gas and Producing Coke, of which the following is a specification.

This invention relates to a novel gas oven having vertical coking chambers and regenerators arranged on an even level therewith, this application being a division of an application filed by me July 28, 1913 under Serial Number 781,463.

According to the present invention, the heating of the coking chambers is effected by means of a plurality of horizontally disposed substantially U-shaped heating flues arranged above one another and surrounding said chambers preferably at three sides thereof. These heating flues communicate with regenerators also arranged above one another and separated by intervening horizontal partitions, so that zones of different heat intensity may be formed at the different levels of the coking chambers.

In the accompanying drawing: Figure 1 is a vertical section through an oven embodying my invention, and Fig. 2 a horizontal section thereof.

The two adjacent oven chambers *b'* are surrounded at three sides by the heating flues *f'*. The latter are connected by nozzle-like passages *g'* to the regenerators *h'* and *i'*. The operation is such that the outer regenerators *h'* at one level are fed with gas and air, while the two central regenerators *i'* of the same level serve to discharge the heat. When the direction of flow of the gas is reversed after about half an hour, the two central regenerators *i'* are fed with gas and air, while the four outer regenerators *h'* serve to accumulate the heat. The distribution of the gases is effected by slides *s* which are adjusted from the exterior, according to observations made through the inspection holes *t*. The several regenerators *h', i'* are divided at different levels by substantially horizontal partitions into superposed compartments or zone regenerators, each of said compartments being directly connected to the heating flues *f'*.

The passage of the gases from the distributing chambers *n', o'* to the several zone

regenerators is controlled by valves such as rotary valves *l', m'*. In this manner, the heat may be so regulated that for instance, the central zone where coking commences, may be more intensely heated than the other zones. It is hereby important that the regulation of the gases should be effected before they enter the regenerators, *i. e.* before they are heated, while at the other side, the escaping gases should not pass out until they have delivered up most of their heat. At these points however, the temperature is comparatively low so that the regulation can be effected with ease and certainty while maintaining the fundamental distribution in the regenerators. With this arrangement, the inclination of the sides of the oven chamber is greater at the top than at the low part so that jamming of the coke owing to its greater expansion at this part due to the greater heat at the upper part of the oven is avoided.

What I claim as my invention and desire to secure by Letters Patent of the United States is:—

1. In an oven for the generation of gas and production of coke, an upright coking chamber, a plurality of regenerators located above one another sidewise of the coking chamber, and a plurality of coking chamber-heating flues also located above one another and communicating with said regenerators.

2. An oven for the generation of gas and production of coke, comprising a plurality of upright coking chambers, heating walls for said chambers, each of said walls being provided with a plurality of heating flues arranged above one another and extending in a substantially horizontal direction, and a plurality of zone regenerators arranged above one another and communicating with said heating flues.

3. An oven for the generation of gas and production of coke, comprising a plurality of upright coking chambers, heating walls for said chambers, each of said walls being provided with a plurality of heating flues arranged above one another and extending in a substantially horizontal direction, a plurality of zone regenerators also arranged above one another and communicating with said heating flues, and means independent of

each other for regulating the admission of the heating media to the several regenerators.

4. An oven for the generation of gas and production of coke, comprising a plurality of upright coking chambers, heating walls for said chambers, and provided with a plurality of substantially U-shaped heating flues arranged above one another and extending in a substantially horizontal direction, a plurality of zone regenerators also arranged above one another and communicating with said heating flues, and means independent of each other for regulating the admission of the heating media to the several regenerators.

5. An oven for the generation of gas and production of coke, comprising a plurality of upright coking chambers arranged side by

side, heating walls for said chambers, each 20 of said walls being provided with a plurality of heating flues arranged above one another and extending in a substantially horizontal direction, a plurality of zone regenerators also arranged above one another 25 and communicating with said heating flues, the zone regenerators being located at the same level with the coking chambers and distributed over substantially the entire height thereof, and means independent of 30 each other for regulating the admission of the heating media to the several regenerators.
